United States Patent

Des. 235,700
Patented July 8, 1975

235,700

SPORT SHOE

Jonas Senter, Oakley Lane, Greenwich, Conn. 06830

Filed June 18, 1974, Ser. No. 480,534

Term of patent 14 years

Int. Cl. D2—04

U.S. Cl. D2—311

FIG. 1 is a side perspective view of a sport shoe showing my new design;

FIG. 2 is a bottom front perspective view thereof;

FIG. 3 is a side elevational view;

FIG. 4 is a rear elevational view; and

FIG. 5 is a bottom plan view.

I claim:

The ornamental design for a sport shoe, as shown.
